CLAIM

The ornamental design for oral vaporizer, as shown and described.

DESCRIPTION

FIG. 1 is a top perspective view of a first embodiment of the oral vaporizer;

FIG. 2 is a bottom perspective view of the first embodiment of the oral vaporizer;

FIG. 3 is a top view of the first embodiment of the oral vaporizer;

FIG. 4 is a bottom view of the first embodiment of the oral vaporizer;

FIG. 5 is a left side view of the first embodiment of the oral vaporizer;

FIG. 6 is a right side view of the first embodiment of the oral vaporizer;

FIG. 7 is a front view of the first embodiment of the oral vaporizer;

FIG. 8 is a rear view of the first embodiment of the oral vaporizer;

FIG. 9 is a top perspective view of the first embodiment of the oral vaporizer in the open position;

FIG. 10 is a top perspective view of a second embodiment of the oral vaporizer;

FIG. 11 is a bottom perspective view of the second embodiment of the oral vaporizer;

FIG. 12 is a top view of the second embodiment of the oral vaporizer;

FIG. 13 is a bottom view of the second embodiment of the oral vaporizer;

(Continued)

FIG. 14 is a left side view of the second embodiment of the oral vaporizer;
 FIG. 15 is a right side view of the second embodiment of the oral vaporizer;
 FIG. 16 is a front view of the second embodiment of the oral vaporizer;
 FIG. 17 is a rear view of the second embodiment of the oral vaporizer; and
 FIG. 18 is a top perspective view of the second embodiment of the oral vaporizer in the open position;
 FIG. 19 is a top perspective view of a third embodiment of the oral vaporizer;
 FIG. 20 is a bottom perspective view of the third embodiment of the oral vaporizer;
 FIG. 21 is a top view of the third embodiment of the oral vaporizer;
 FIG. 22 is a bottom view of the third embodiment of the oral vaporizer;
 FIG. 23 is a left side view of the third embodiment of the oral vaporizer;
 FIG. 24 is a right side view of the third embodiment of the oral vaporizer;
 FIG. 25 is a front view of the third embodiment of the oral vaporizer;
 FIG. 26 is a rear view of the third embodiment of the oral vaporizer;
 FIG. 27 is a top perspective view of the third embodiment of the oral vaporizer in the open position;
 FIG. 28 is a top perspective view of a fourth embodiment of the oral vaporizer;
 FIG. 29 is a bottom perspective view of the fourth embodiment of the oral vaporizer;
 FIG. 30 is a top view of the fourth embodiment of the oral vaporizer;
 FIG. 31 is a bottom view of the fourth embodiment of the oral vaporizer;
 FIG. 32 is a left side view of the fourth embodiment of the oral vaporizer;
 FIG. 33 is a right side view of the fourth embodiment of the oral vaporizer;
 FIG. 34 is a front view of the fourth embodiment of the oral vaporizer;
 FIG. 35 is a rear view of the fourth embodiment of the oral vaporizer; and
 FIG. 36 is a top perspective view of the fourth embodiment of the oral vaporizer in the open position.
 The dash-dash broken lines in the drawings illustrate portions of the oral vaporizer which form no part of the claimed design. The dot-dash broken lines in the drawings illustrated

where elements of the article disassemble when in the open position and form no part of the claimed design.
